UNITED STATES PATENT OFFICE.

WILHELM SCHEERER, OF TUTTLINGEN, GERMANY, ASSIGNOR TO THE
ACTIEN-GESELLSCHAFT FÜR FEIN MECHANIC, VORMALS JETTER &
SCHEERER, OF SAME PLACE.

BOTTLE-CLOSURE.

SPECIFICATION forming part of Letters Patent No. 570,342, dated October 27, 1896.

Application filed January 30, 1896. Serial No. 577,422. (No model.)

To all whom it may concern:

Be it known that I, WILHELM SCHEERER, of Tuttlingen, Würtemberg, Germany, have invented a new and useful Bottle-Closure, of 5 which the following is a specification.

My invention relates to an improvement in bottle-closures.

The object of my invention is to produce a bottle - closure which may be manipulated 10 with one hand and which will seal the bottle in a perfect manner, my invention being especially applicable to bottles whose contents it is desired to maintain in a sterilized condition.

15 My invention consists in the features, details of construction, and combination of parts which will first be described in connection with the accompanying drawings, and then particularly pointed out in the claims.

20 In the drawings, Figure 1 represents a longitudinal sectional view of a bottle provided with one form of device embodying my invention; Fig. 2, an elevation of the same; Fig. 3, a detail sectional view of that form of 25 cap illustrated in Fig. 1; Fig. 4, a similar view illustrating another form of cap and hood embodying my invention, and Fig. 5 a detail sectional view of the hood shown in Fig. 4.

30 Referring to the drawings, A is a bottle provided with an enlargement *a*, whereby a shoulder is formed on the neck of the bottle for purposes hereinafter described. On the enlargement, which is beveled or coned, 35 as shown, is placed a cap C C', which is provided with a peripheral recess *c*, as shown in Figs. 1 and 3, or with two such recesses *c c'*, as shown in Fig. 4.

30 The cap C C' may bear against a cork E, 40 which is inserted into the mouth of the bottle or into a tube B, which itself projects into the bottle-mouth. Around the cap and projecting below the lower edge of the same is placed an elastic hood or holding device 45 which may be either cup-shaped, as shown at D in Figs. 1 and 2, or tubular, as shown at D' in Figs. 4 and 5. In the former case the hood or holding device D is placed over the cap and projects some distance below the

lower edge of the said cap, being provided at 50 its lower edge with an enlargement or projection *d*, which is arranged to engage the under side of the bottle neck or shoulder and thus securely hold the cap C down upon the stopper or cork E, thereby retaining the same 55 in place, while at the same time the air is excluded from the bottle.

By rolling up the lower projecting edge of the elastic hood or holding device until it reaches the peripheral recess *c* the said projecting edge will be retained in its rolled condition because of the enlargement *d*, whose elasticity will force the roll into the said recess. In this condition the cap, with the hood, 60 may be raised from the bottle, thereby permitting the removal of the cork or stopper. To close the bottle, the cap is replaced and the projecting edge unrolled until the enlarged portion *d* comes below the shoulder *a*. By this construction, as will be fully understood, the elastic hood and cap may be manipulated by one hand in opening or closing the bottle, and the hood is held in its rolled 70 position when the cap is removed from the bottle. 75

In the second form of construction the hood or holding device is not cup-shaped, but tubular, and instead of passing over the upper end of the cap is provided with an enlargement at its upper edge, as shown at *d'*, 80 Figs. 4 and 5, which upper enlargement enters the upper recess *c'*, Fig. 4, thus holding the hood to the cap C'. 85

Having thus fully described my invention, what I claim, and desire to secure by Letters Patent, is—

1. In a bottle - closure, the combination, with a cap having a recess in its periphery, of an elastic hood connected to the cap and projecting below the same, said hood having 90 an enlargement at its lower end arranged to engage the neck of the bottle and to hold the projecting portion of the hood in the recess in the cap when said portion is rolled up, substantially as set forth. 95

2. In a bottle - closure, the combination, with a cap having a pair of recesses in its periphery, of an elastic hood provided with

an enlargement arranged to enter the upper recess and hold the hood to said cap, said hood also having an enlargement at its lower end arranged to engage the neck of the bottle and to roll up into the lower recess in the cap, substantially as set forth.

5 In testimony whereof I have signed this

specification in the presence of two subscribing witnesses.

WILHELM SCHEERER.
